UNITED STATES PATENT OFFICE.

CHARLES H. MUCKENHIRN, OF DETROIT, MICHIGAN.

DESIGN FOR A REAR-LAMP LENS.

Application filed July 9, 1923. Serial No. 6,734. Term of patent 7 years.

To all whom it may concern:

Be it known that I, CHARLES H. MUCKENHIRN, a citizen of the United States, residing at Detroit, in the county of Wayne and State of Michigan, have invented a new, original, and ornamental Design for Rear-Lamp Lens, of which the following is a specification, reference being had to the accompanying drawings, forming part hereof.

In the drawings:

Figure 1 is a front elevation, and

Figure 2 is a side edge view, of a rear lamp lens showing my new design.

The raised panel portion is adapted to bear or have formed thereon the name of make of automobile.

I claim:

The ornamental design for a rear lamp lens as shown.

CHARLES H. MUCKENHIRN.
